UNITED STATES PATENT OFFICE.

WILLIAM WORTH BURSON, OF CHICAGO, ILLINOIS.

TUBULAR KNIT GOODS.

SPECIFICATION forming part of Letters Patent No. 715,457, dated December 9, 1902.

Application filed June 6, 1896. Serial No. 594,485. (Specimens.)

To all whom it may concern:

Be it known that I, WILLIAM WORTH BURSON, a citizen of the United States, residing at Chicago, in the county of Cook and State 5 of Illinois, have invented certain new and useful Improvements in Tubular Knit Goods, of which the following is a specification, reference being had therein to the accompanying drawings.

10 This invention will be described first with reference to the accompanying drawings, after which its distinguishing characteristics will be more particularly pointed out and distinctly defined in the claims at the close of 15 this specification.

Figure 1 of the drawings shows a knit stocking. Fig. 2 shows a doubled yarn composed of right-hand twist and left-hand twist single yarns, as described hereinafter, produced by doubling and twisting. Fig. 3 is a view showing how the component yarns may be combined on a knitting-machine. Figs. 4 and 5 are diagrams on an enlarged scale, 20 showing portions of knit fabrics embodying 25 my invention.

In the manufacture of tubular knit goods considerable trouble is experienced from the tendency of the vertical rows or lines of stitches, instead of lying in straight lines 30 lengthwise of the goods, to assume an inclined or oblique direction spirally around the latter. This tendency of the fabric to twist is especially objectionable in the case 35 of stockings and the like which have been knit upon straight-knitting machines having opposite and parallel rows of needles. Such fabrics are composed of two halves, united along lines at the opposite edges thereof and frequently are widened or narrowed along one 40 of such lines of union. The tendency to twist aforesaid causes these lines of union aforesaid to assume a spiral direction in the fabric.

The object of my invention is to produce knit goods, such as stockings and other articles of apparel, which shall be free from the 45 objection aforesaid.

In accordance with my invention I employ in the knitting of goods a doubled yarn composed of a single yarn of right-hand twist and 50 a single yarn of left-hand twist combined with each other. The said single yarns may be separately wound upon cones or bobbins,

as represented in Fig. 3, and united as they are led to the knitting-machine, in which they are knit together into the desired fabric. 55 When thus drawn off their respective bobbins and passed together through the yarn-guides of the knitting-machine, the yarns will twist together slightly in consequence of the action of the machine as the doubled 60 yarns are delivered to the needles by the traveling yarn-guide. In this instance one turn of twist will be put into the doubled yarns for each round of the machine. The length of yarn knit in one round is so great 65 that this single turn will not be apparent, and consequently the yarns will lie substantially parallel with each other, as meant to be indicated in Fig. 4. If desired, the yarns may first be doubled and twisted and wound 70 upon cones or bobbins before being taken to the knitting-machine. The doubled and twisted yarn is represented in Fig. 2. The fabric knit therefrom is represented in Fig. 5.

By the use of a doubled yarn such as herein 75 shown and described a tubular fabric may be produced which will lie straight and flatwise and without twist no matter how hard the twist of the single yarns may be, thus permitting the use of harder-twisted yarns 80 than heretofore employed. The lines along which the opposite halves or portions of the fabric are joined or knit together will lie naturally at the sides or edges of the flattened tube, and the line of widenings or narrowings will remain in its proper place along 85 one of the sides or edges.

I claim as my invention—

1. Tubular knit goods knit of doubled yarn composed of component yarns having respectively a right-hand twist and a left-hand twist, substantially as described. 90

2. In knitted or netted fabrics, meshes or loops made from yarns or threads twisted in mutually opposite directions throughout the 95 fabric.

3. In knitted or netted fabrics, rows of meshes or loops made from yarns or threads strongly twisted in mutually opposite directions throughout the fabric. 100

4. In a knitted or netted fabric or garment made therefrom, a row of meshes made from a multiple yarn or thread, one or more component yarns of which are twisted in one di-

- rection and one or more in an opposite direction.
5. In a knitted or netted fabric or garment made therefrom, a series of rows or meshes each made from a multiple yarn or thread, one or more component yarns of which are twisted in one direction and one or more in the opposite direction.
6. In knitted or netted fabrics, meshes made from a neutral multiple thread having component yarns or threads individually twisted in opposite directions, all the component yarns being moreover twisted together into a united yarn.
- 15 7. In knitted or netted fabrics, meshes made from a multiple yarn or thread consisting of two yarns or sets of yarns individually twist-

ed in opposite directions, said yarns being, moreover, twisted together, the resultant twisting tendencies in the component yarn being in equilibrium. 20

8. In knitted or netted fabrics, a series of rows of meshes, each made from a neutral multiple thread having component yarns or threads individually twisted in opposite directions, all the component yarns being, moreover, twisted together into one united yarn. 25

In testimony whereof I affix my signature in presence of two witnesses.

WILLIAM WORTH BURSON.
